COIN-CONTROLLED TELEPHONE LOCK

Application filed April 18, 1928. Serial No. 271,027.

This invention relates to coin-controlled telephone locks, and has for an object the provision of a lock for preventing the use of a telephone without the insertion of a suitable 5 coin within a slot provided for that purpose.

Another object is the provision of a telephone lock of the character described, adapted for use in connection with automatic, or "dial" telephones.

10 Another object is the provision of a lock of the character described, from which it is possible to regain the coin if, for any reason, the receiver of the telephone is not lifted from its hook after the coin has been inserted 15 into its slot.

Another object is the provision of a telephone lock of the character described, which depends for its operation upon the force of gravity, and yet which is provided with 20 means for preventing defeat of the purpose of the lock by inverting the telephone and lock mechanism.

A still further object is the provision of a 25 telephone lock of the general character described, which is provided with means for positively preventing use of the telephone, irrespective of whether the proper coin is inserted or not; it being understood that the lock is so constructed that after a coin has 30 been dropped in the slot and it is found that the telephone is still unavailable for use, the coin can be regained.

This invention possesses other objects and 35 features of advantage, some of which, with the foregoing, will be set forth in the following description of the preferred form of the invention which is illustrated in the drawings accompanying and forming part of the specification. It is to be understood that I do not 40 limit myself to the showing made by the said drawings and description, as I may adopt variations of the preferred form within the scope of my invention as set forth in the 45 claims.

Referring to the drawings:

Figure 1 is a side elevation of a desk telephone instrument of the automatic or "dial" type, with the lock of my invention in operative 50 position thereupon.

Fig. 2 is a front elevation of the instrument and lock of Fig. 1.

Fig. 3 is a side elevation of the instrument and lock, the direction of view being opposite to that of Fig. 1.

Fig. 4 is an enlarged side elevation similar to Fig. 1, with the telephone receiver and cover plate of the lock housing removed and a portion of the receiver hook broken away to better reveal the operative parts of the lock 60 which are shown in normal, or dial locking position.

Fig. 5 is a view similar to Fig. 4, a portion of the figure being broken away to reduce its 65 length, and showing the position of the operative parts of the lock after the proper coin has been inserted, but before the receiver has been lifted from the hook.

Fig. 6 is a view similar to Fig. 5, showing the opposite parts of the lock in the position 70 assumed by them immediately after the receiver has been lifted from the hook.

In terms of broad inclusion, the lock of my invention comprises a detent movable to engage within one of the apertures in the dial 75 of an automatic telephone instrument, to prevent operation of the dial as is necessary in placing a call. The detent is operatively connected to a bar for movement therewith; and the bar is arranged to be engaged under 80 the receiver hook of the instrument so that the bar and detent will be retained in dial locking position until the receiver hook is raised. Means are provided for retaining the bar in lowered position, irrespective of 85 the position of the receiver hook until a suitable coin has been inserted in a slot provided in the housing of the lock; and a locked compartment is arranged in the lower part of the housing for the reception of all such 90 coins after they have been released by the locking mechanism, which is so arranged that each coin is not released until after the receiver has been lifted from the hook, with the result that if the receiver is not taken 95 from the hook after the coin has been dropped, it will be possible to regain the coin.

In greater detail, the device of the present invention is shown mounted upon a conventional telephone instrument having a mouth- 100

piece 6 supported upon a standard 7 and base 8, and a receiver 9 adapted to be hung upon a receiver hook 11 which is vertically movable within a slot 12 in the standard 7. This instrument is of the automatic type; and is provided with a dial 13 provided with a plurality of apertures 14, and which may be operated after the receiver 9 has been lifted from its hook 11 to place a call; it being understood that the receiver hook 11 is resiliently urged upwards, and that the electric circuit connecting the instrument to the central station, is established automatically when the hook 11 is lifted. The weight of the receiver 9 is such that when hung upon the hook 11, it will retain the hook 11 in lowered position against the action of the resilient means tending to raise the hook.

The lock of the present invention is enclosed in a housing 16 having a bracket 17 adapted to be extended around the standard 7 and securely locked in position thereupon by screws 18 or their equivalent.

A bar 21 is disposed vertically within the housing 16, and is capable of longitudinal sliding movement. The upper end 22 of the bar 21 extends through a suitable slot in the top of the housing 16 to a position closely below the arm 23 of the receiver hook 11. The effective length of the bar 21 may be varied by turning an adjusting screw 24 which is threaded into the top of the bar 21, and then tightening a locking nut 26 to retain the screw 24 in adjusted position. The screw 24 should be adjusted so that the bar 21 is moved to its lowermost position when the hook 11 is lowered to the position occupied thereby when the receiver 9 is supported thereupon.

An arm 27 is mounted for rotary movement upon a pivot pin 28 which is rigid with the housing 16 and passes loosely through the arm 27 adjacent one end 29 thereof. A pivot pin 31 joins the lower end 32 of the bar 21 to the arm 27 at a point between the pivot pin 28 and the outer end 33 of the arm 27; and a coil spring 34 is under tension between a bracket 36 rigid with the bottom of the housing 16 and the end 29 of the arm 27, with the result that the arm 27 is continually urged to rotate upon the pivot pin 28 in that direction which will raise the bar 21.

A detent 37 is pivoted at its upper end to the outer end 33 of the arm 27 as by a pivot pin 38, and depends therefrom through a slot in the bottom of the housing 16 in such position that its lower end 39 normally is inserted in one of the holes 14 in the dial 13, effectually preventing rotation thereof.

Coin releasable means for locking the bar 21, and with it the detent 37, in dial locking position, are provided. A shoulder 41 is formed adjacent the lower end 32 of the bar 21. A lever 42 is pivoted by a pivot pin 43 to the housing 16 at a point higher than the shoulder 41 and slightly to one side of the

bar 21, and is provided at one end with a ratchet 44 extending downwards therefrom to engage the shoulder 41 and hold the bar 21 against upward movement when the lever 42 and ratchet 44 are in the position shown in Fig. 4. A second ratchet 46 extends upwards from the same end of the lever 42; and a second shoulder 47 is provided upon the bar 21 above the shoulder 41 and higher than the pivot pin 43. The proportionate size and arrangement of the ratchet 46 and shoulder 47 is such that if the lever 42 is rotated upon its pivot pin 43 in the direction which will cause the ratchet 44 to release the shoulder 41, and the bar 21 left in lowermost position as would be the case if the receiver 9 were not taken from the hook 11, the ratchet 46 would engage upon the top of the shoulder 47 and stop the rotational movement of the lever 42 before the lever has completed all the movement of which it is capable.

The relative position occupied by the parts when the ratchet 46 is engaged upon the top of the shoulder 47 as described, is shown in Fig. 5. The parts are so proportioned that the weight of the ratchets 44 and 46 destroys the stable equilibrium of the lever 42 upon its pivot pin 43, and causes the lever to move to the position occupied thereby when the ratchet 44 engages the shoulder 41. A coin chute 51 accessible through a slot 52 in the housing 16, is inclined downwards from the slot 52, and is provided with an opening 53 in its lower end above the other end 54 of the lever 42. The housing 16 is so restricted adjacent this point that when a coin 56 drops through the opening 53, it is retained upon the end 54 of the lever 42; and the ratchets 44 and 46 are so designed that the turning moment about the pivot pin 43 resulting from their weight, is less than the turning moment resulting from the weight of the coin 56 when supported upon the end 54 of the lever 42. As a result, when the coin 56 strikes the end 54 of the lever 42, the lever 42 is rotated upon the pin 43 so that the ratchet 44 releases the shoulder 41. When this takes place however, the ratchet 46 will impinge upon the top of the shoulder 47 as previously described, limiting the movement of the lever 42; and the length of the lever 42 is such that its end 54 is spaced from a wall 57 of the housing 16 a distance less than the diameter of the coin 56.

Owing to the restriction of the housing 16 adjacent this point, it is necessary for the coin 56 to pass between the end 54 of the lever 42 and the wall 57, in order for it to be released from the lever 42; and accordingly, the coin 56 will not drop past the lever 42 until the bar 21 has been elevated sufficiently to release the ratchet 46 from the shoulder 47, permitting the ratchet 46 to drop into the space 58 between the shoulders 41 and 47, as shown in Figure 6.

After the lever 42 has been permitted to

rotate upon its end 43 to the position shown in Fig. 6, the coin 57 is permitted to drop upon a lip 59 which extends from the bottom of a slot 61 to guide the coin 56 into a compartment 62, access to the interior of which may be had by operating a lock 63 to release the door 64 thereof.

Since the rotation of the lever 42 upon its pivot pin 43 is dependent upon the force of gravity, I have provided means for preventing the movement thereof to releasing position by inverting the telephone instrument, and with it the lock housing and mechanism. A lever 66 is pivoted at one end by a pin 67, and is provided with a weight 68 at its other end. The pin 67 is positioned upon the housing 16 closely below the pin 43; and the weight 68 is positioned closely below the end 54 of the lever 42. Normally, the weight 68 holds the lever 66 down away from the lever 42, but should the instrument be inverted, it would be found that the weight 68 would cause the lever 66 to drop onto the end 54 of the lever 42; and the weight 68 is sufficiently great so that its turning moment about the pin 43 would then be greater than that of the ratchets upon the other end of the lever 42, with the result that the ratchet 44 would not gravitate out of engagement with its associated shoulder 41.

Means are also provided for locking the instrument against use, irrespective of whether the proper coin is inserted or not. A bracket 71 is mounted for pivotal movement with a pin 72 which extends through a wall of the housing 16 into the compartment 62, where it is provided with a knob 73 by means of which the pin 72 and bracket 71 may be turned. Thus the bracket 71 may be operated from within the compartment 62 to place it optionally in engagement with, or release it from the end 29 of the arm 27.

When the bracket 71 is engaged with the end 29, the arm is positively locked against rotational movement, with the result that the detent 27 can not be removed from the dial 13. When so locked, the bar 21 is similarly locked against longitudinal displacement, with the result that when the lever 42 is rotated by having the weight of a coin 56 imposed upon the end 54 thereof, the ratchet 46 will impinge upon the top of the shoulder 47 as above described, making it impossible for the coin 56 to pass the end 54, so that the person who drops the coin can recover it simply by inverting the instrument.

I will now proceed with a description of the manner in which my improved telephone lock operates. Normally, the operative parts of the lock occupy the position indicated in Fig. 6. When it is desired to place a call over the telephone instrument, a suitable coin 56 should be inserted through the slot 52 into the coin chute 41. When the coin 56 reaches

51, it will drop upon the end 54 of the lever 42 and be retained thereupon by the restricted housing 16 and wall 57, with the result that the lever 42 is rotated upon its pivot pin 43 until the ratchet 46 impinges upon the top of the shoulder 47. This of course, also results in the release of the shoulder 41 by the ratchet 44; but since the receiver 9 has not yet been removed from the hook 11, the bar 21 is still retained in lowered position. This 70 fact facilitates removal of the ratchet 44 from the shoulder 41, because of the fact that otherwise friction between the two might hamper their relative movement.

Now, when the receiver 9 is removed from the hook 11, as is necessary before dialing, the bar 21 will be raised through the action of the coil spring 34. As this takes place, the end 33 of the arm 27 is also raised, and with it the detent 27, with the result that the dial 13 may now be rotated to place the desired call.

As the bar 21 moves to its uppermost position, the shoulder 47 moves out from under the ratchet 46, permitting the lever 42 to complete its rotary movement. Thus the space between the end 54 of the lever 42 and the wall 57, is increased sufficiently to permit the coin 56 to drop therewith through the slot 61 into the compartment 62. This of course, 95 relieves the lever 42 of the weight of the coin 56, permitting it to drop back so that the ratchet 46 is out from under the shoulder 47. As a result, when the call is completed and the receiver 9 placed back upon the hook 11, 100 the arm 21 will be forced downwards again against the action of the spring 36, and with it, the detent 27 to dial-engaging position. The ratchet 44 will then drop into engagement with the shoulder 41 again, to prevent 105 operation of the instrument without again inserting the necessary coin.

I claim:

1. A lock for a telephone instrument having a rotatable dial and a vertically movable receiver hook mounted thereon, said lock comprising a housing adapted to be rigidly mounted upon said instrument, a bar slidably mounted within said housing with its upper end extending therethrough to engage 110 said receiver hook and be lowered thereby when the hook is lowered, an arm pivotally mounted adjacent one end within the housing and pivoted intermediate its ends to said bar, and a detent depending from and pivoted at its upper end to the other end of said arm, the lower end of said detent extending through the housing to engage within a hole in said dial when in lowered position, and releasable means locking said detent in dial 115 engaging position.

2. A lock for a telephone instrument having a rotatable dial and a vertically movable receiver hook mounted thereon, said lock comprising a housing adapted to be rigidly 120

mounted upon said instrument, a bar slidably mounted within said housing with its upper end extending therethrough to engage said receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, means for locking said detent in lowered position, means urging said detent to elevated position, and 10 coin-controlled means for releasing said locking means.

3. A lock for a telephone instrument having a rotatable dial and a vertically movable receiver hook mounted thereon, said lock comprising a housing adapted to be rigidly mounted upon said instrument, a bar slidably mounted within said housing with its upper end extending therethrough to engage said receiver hook and be lowered thereby when 20 the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a spring urging said detent to elevated position, a shoulder on said bar, a lever pivotally mounted intermediate its ends within said housing, a ratchet rigid with one 25 end of said lever and adapted to engage said shoulder to retain the bar in lowered position, the weight of said ratchet serving to destroy the stable equilibrium of said lever and impart rotary movement to it upon its pivot to lower the ratchet into engagement with said shoulder, and coin-controlled means for elevating the ratchet end of said lever to release said bar.

25 4. A lock for a telephone instrument having a rotatable dial and a vertically movable receiver hook mounted thereon, said lock comprising a housing adapted to be rigidly mounted upon said instrument, a bar slidably mounted within said housing with its upper end extending therethrough to engage said receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a spring urging said detent to elevated position, a shoulder on said bar, a ratchet pivotally mounted in said housing to engage said shoulder and retain the bar in lowered position, and coin-controlled means for withdrawing said ratchet from said shoulder.

40 5. A lock for a telephone instrument having a rotatable dial and a vertically movable receiver hook mounted thereon, said lock comprising a housing adapted to be rigidly mounted upon said instrument, a bar slidably mounted within said housing with its upper end extending therethrough to engage said receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a spring urging said detent to elevated position, a shoulder on said bar, a lever pivotally mounted intermediate its ends within said housing, a ratchet rigid with one end of said lever and adapted to engage said shoulder to retain the bar in lowered position, and coin-controlled means for disengaging said ratchet from said shoulder.

60 6. A lock for a telephone instrument having a rotatable dial and a vertically movable receiver hook mounted thereon, said lock comprising a housing adapted to be rigidly mounted within said housing with its upper end extending therethrough to engage said

70 mounted upon said instrument, a bar slidably mounted within said housing with its upper end extending therethrough to engage said receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a spring urging said detent to elevated position, a shoulder on said bar, a lever pivotally mounted intermediate its ends within said housing, a ratchet rigid with one end of said lever and adapted to engage said shoulder to retain the bar in lowered position, the weight of said ratchet serving to destroy the stable equilibrium of said lever and impart rotary movement to it upon its pivot to lower the ratchet into engagement with said shoulder, and coin-controlled means for elevating the ratchet end of said lever to release said bar.

75 7. A lock for a telephone instrument having a rotatable dial and a vertically movable receiver hook mounted thereon, said lock comprising a housing adapted to be rigidly mounted upon said instrument, a bar slidably mounted within said housing with its upper end extending therethrough to engage said receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a spring urging said detent to elevated position, a shoulder on said bar, a lever pivotally mounted intermediate its ends within said housing, a ratchet rigid with one end of said lever and adapted to engage said shoulder to retain the bar in lowered position, the weight of said ratchet serving to destroy the stable equilibrium of said lever and impart rotary movement to it upon its pivot to lower the ratchet into engagement with said shoulder, and an inclined coin chute accessible at its upper end through a slot in the housing and having an opening in its lower end above the other end of said lever to deposit coins from the chute upon the lever, said lever and ratchet being so proportioned that the turning moment resulting from the weight of the ratchet is less than that resulting from the weight of the coin.

80 8. A lock for a telephone instrument having a rotatable dial and a vertically movable receiver hook mounted thereon, said lock comprising a housing adapted to be rigidly mounted upon said instrument, a bar slidably mounted within said housing with its upper end extending therethrough to engage said

receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a spring urging said detent to elevated position, a shoulder on said bar, a lever pivotally mounted intermediate its ends within said housing, a ratchet rigid with one end of said lever and adapted to engage said shoulder to retain the bar in lowered position, the weight of said ratchet serving to destroy the stable equilibrium of said lever and impart rotary movement to it upon its pivot to lower the ratchet into engagement with said shoulder, and an inclined coin chute accessible at its upper end through a slot in the housing and having an opening in its lower end above the other end of said lever to deposit coins from the chute upon the lever, said housing being restricted to retain the coin upon the lever until the lever is rotated upon its pivotal mounting, said lever and ratchet being so proportioned that the turning moment resulting from the weight of the ratchet is less than that resulting from the weight of the coin.

8. A lock for a telephone instrument having a rotatable dial and a vertically movable receiver hook mounted thereon, said lock comprising a housing adapted to be rigidly mounted upon said instrument, a bar slidably mounted within said housing with its upper end extending therethrough to engage said receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a spring urging said detent to elevated position, a shoulder on said bar, a lever pivotally mounted intermediate its ends within said housing, a ratchet rigid with one end of said lever and adapted to engage said shoulder to retain the bar in lowered position, the weight of said ratchet serving to destroy the stable equilibrium of said lever and impart rotary movement to it upon its pivot to lower the ratchet into engagement with said shoulder, an inclined coin chute accessible at its upper end through a slot in the housing and having an opening in its lower end above the other end of said lever to deposit coins from the chute upon the lever, said housing being restricted to retain the coin upon the lever until the lever is rotated upon its pivotal mounting, said lever and ratchet being so proportioned that the turning moment resulting from the weight of the ratchet is less than that resulting from the weight of the coin, a locked compartment below said lever for the reception of coins therefrom, and means for preventing coins from passing the lever until said receiver hook is raised to permit the bar to be elevated.

10. A lock for a telephone instrument having a rotatable dial and a vertically movable receiver hook mounted thereon, said lock comprising a housing adapted to be rigidly mounted upon said instrument, a bar slidably mounted within said housing with its upper end extending therethrough to engage said receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a spring urging said detent to elevated position, a shoulder on said bar, a lever pivotally mounted intermediate its ends within said housing, a

ratchet rigid with one end of said lever and adapted to engage said shoulder to retain the bar in lowered position, the weight of said ratchet serving to destroy the stable equilibrium of said lever and impart rotary movement to it upon its pivot to lower the ratchet into engagement with said shoulder, a second shoulder upon the bar above said first mentioned shoulder, another ratchet carried by 5 said lever in position to engage said upper shoulder and limit the rotary movement of said lever until the bar has been released by the receiver hook and elevated by said spring, an inclined coin chute accessible at its upper 10 end through a slot in the housing and having an opening in its lower end above the other end of said lever to deposit coins from the chute upon the lever, said housing being restricted to retain the coin upon the lever until 15 the lever is rotated upon its pivotal mounting past the position occupied thereby when engaged by said upper shoulder, said lever and ratchets being so proportioned that the turning moment resulting from the weight of the 20 ratchets is less than that resulting from the weight of the coin, and a locked compartment below said lever for the reception of coins therefrom, means operable from within said locked compartment for locking said bar against movement irrespective of the position of said lever, and a weight pivoted within said housing below said lever to engage the lever and prevent movement thereof by gravity when the housing is inverted. 25

12. A lock for a telephone instrument, having a rotatable dial, and a vertically movable receiver hook mounted thereon, said lock comprising a housing adapted to be rigidly mounted upon said instrument, a bar slidably mounted within said housing with its upper end extending therethrough to engage said receiver hook and be lowered thereby when the hook is lowered, an arm pivotally mounted adjacent one end within the housing and pivoted intermediate its ends to said bar, a detent depending from and pivoted at its upper end to the other end of said arm, the lower end of said detent extending through the housing to engage within a hole in said dial when in lowered position, a shoulder on said bar, a lever pivotally mounted intermediate its ends within said housing, a ratchet rigid with one end of said lever and adapted to engage said shoulder to retain the bar in lowered position, the weight of said ratchet serving to destroy the stable equilibrium of said lever and impart rotary movement to it upon its pivot to lower the ratchet into engagement with said shoulder, a second shoulder upon the bar above said first mentioned shoulder, another ratchet carried by said lever in position to engage said upper shoulder and limit the rotary movement of said lever until the bar has been released by the receiver hook and elevated by said spring, an inclined coin chute accessible at its upper end through a slot in the housing and having an opening in its lower end above the other end of said lever to deposit coins from the chute upon the lever, said housing being restricted to retain the coin upon the lever until the lever is rotated upon its pivotal mounting past the position occupied thereby when engaged by said upper shoulder, said lever and ratchets being so proportioned that the turning moment resulting from the weight of the ratchets is less than that resulting from the weight of the coin, a locked compartment below said lever for the reception of coins therefrom, and means operable from within said locked compartment for locking said bar against movement irrespective of the position of said lever. 30 35 40 45 50 55 60 65 70 75 80 85 90 95 100 105 110 115 120 125 130

13. In a lock for a telephone instrument having a movable receiver hook and a call dial, a bar engaging said hook to be moved thereby when the hook moves in one direction, a detent operably associated with said bar to be moved thereby into locking engagement with said dial, means urging said detent to unlock position, a coin chute, locking means being releasable by a coin deposited in said chute, and means retaining said coin in the chute after the locking means have been released and until said receiver hook and bar have been moved.

14. In a lock for a telephone instrument having a movable receiver hook and a call dial, a bar engaging said hook to be moved thereby when the hook moves in one direction, a detent operably associated with said bar to be moved thereby into locking engagement with said dial, means urging said detent to unlock position, a coin chute, locking means being releasable by a coin deposited in said chute, and means permitting recovery of a deposited coin until the receiver hook and said bar have been moved.

In testimony whereof I have signed my name to this specification.
